UNITED STATES PATENT OFFICE

JOHN E. BLACK, OF RUMSON, NEW JERSEY, ASSIGNOR TO THE BABCOCK & WILCOX COMPANY, OF BAYONNE, NEW JERSEY, A CORPORATION OF NEW JERSEY

AIR HEATER

Application filed March 4, 1926. Serial No. 92,191.

This invention relates to an air heater that is especially useful in connection with steam boilers, and will be understood from the description and the accompanying drawing 5 which shows a vertical section through the device and portion of a steam boiler.

In the drawing, reference character 1 indicates a bank of inclined tubes that are connected to the header 2, which is, in turn, connected to the steam and water drum 3 by means of the nipples 4. Hot products of combustion from the furnace F of the boiler, pass across the tubes 1, and then between the nipples 4, and down along the feed water 15 preheater or economizer 5, as shown by the arrows, and enter the lower ends of the heating elements or tubes 7 of the air heater, and pass out through the smoke stack 8. The tubes 7 are connected to header plates 9 and 10 and 20 are enclosed in a housing that may be rectangular in cross-section, the side walls of which are shown at 11 and 12, with the tubes 7 distributed all the way across between the other two walls.

25 Baffles 13, 14 and 15 as long as the distance between the other two walls, extend across the tubes 7. A plate 16, which is likewise as long as the distance between the two walls, is located between the tubes 7 and wall 12 and 30 is as wide as the distance between baffles 13 and 15. Dampers or closure members 17 are hinged at the ends of the plate 16, and are of such dimensions as to close the spaces between the plate 16 and the wall 12 when they 35 are in the closing positions. Similar dampers 17' are hinged at the ends of the plate 16 and close the spaces between plate 16 and baffles 13 and 15 when they are closed. A damper 18 is hinged near the middle of plate 40 16, and is of sufficient dimensions to close the space between this plate and the edge of the baffle 14. A damper or baffle member 19 is hinged at the wall 11, and is of sufficient dimensions to close the space between the baffle 14 and the wall 11.

45 The air pump or fan 20 forces air through the duct 21 across the heating elements or tubes 7 of the air heater, through the duct 23 into the suction fan or pump 22, from whence 50 the air passes through the duct 24 to the fur-

nace of the boiler, where it is used for combustion purposes, the hot products passing across the boiler tubes 1, as above mentioned.

The operation is as follows: When the boiler is operating at normal load, the dampers 17 and 17' are turned to close the spaces between the plate 16 and the wall 12 and between the plate 16 and the tubes 7, and the damper 18 is also turned to leave the space between the baffle 14 and the plate 16 open, 55 and the damper 19 is turned to close the space between the wall 11 and baffle 14. The air passes, as shown by the arrows, through the duct 21 across the upper ends of the tubes 7, thence in a reverse direction across the tubes 60 between the baffles 13 and 14, thence again across the tubes between the baffles 14 and 15, and finally across the tubes below the baffle 15 into the duct 23 and fan 22, through the duct 24 to the furnace. When the boiler 65 is being forced, a part of the air may be bypassed around the heater by opening the dampers 17, so that a portion of the air does not come into contact with the air heater tubes 7. The dampers 18 and 19 may be adjusted, 70 so that only a portion or none of the air that passes across the upper ends of the tubes 7, passes across the portions between the baffles 13 and 15. The dampers 17, 18 and 19, may be adjusted to different positions 75 to vary the proportions of air that is to be bypassed entirely around the tubes or around a portion of the same, as above described.

In other words it will be seen that the duct and the preheater are arranged in parallel 80 so that the air may follow parallel paths through either the duct or the preheater. The word "parallel" is not here used in a geometrical sense but in the same sense as in describing electrical circuits; that is, there are two 85 paths between the fans 20 and 22 which the air from the fan 20 may take.

With air by-passed around the air heater, it is possible to operate the pressure fan 20 or suction fan 22 at less pressure or suction, 90 respectively, or a larger volume of air can be delivered by the same fans than would be the case if all the air were passed through all the passes of the air heater, with the consequent frictional resistance and drop in air 95 100

pressure. Either one of the fans 20 or 22 may be dispensed with, thus operating the device by forcing air through the heater by the fan 20 when the fan 22 is not used, or 5 by suction of air through the air heater by means of the fan 22, when the fan 20 is not used. When a boiler is operated without a feed water heater, the hot exit gases may be at a sufficiently high temperature to heat the 10 air to such a point as to give trouble at the stoker. In such cases, the dampers of the air heater can be operated so as to prevent the air from being heated to too high a tempera-
ture.

15 By making provision for by-passing some of the air at high ratings, the air velocity at normal ratings can be increased, thereby increasing the efficiency of the air heater surface. If no provision were made for by-passing the air at peak loads, the velocity thereof would be reduced unless extraordinarily large fans and driving means therefor were used. Another advantage of by-passing air at certain loads is that the fans can be designed to run at high average efficiency over wide boiler ratings, as a sufficient amount of air can be by-passed with different boiler ratings to give a somewhat uniform load on the fan.

30 When it is desired to change the heater from a four-pass to a two-pass heater, the dampers 17' are opened, the damper 18 is closed and the damper 19 is opened, thus causing the air to pass over the heating surface of the air heater twice and increasing the area of flow, thereby reducing materially the resistance of flow of the air through the heater, and at the same time utilizing the total surface of the air heater. A portion of the air 40 may be by-passed by opening the dampers 17, whether the heater is operated as a four-pass or as a two-pass air heater.

I claim:

1. A fluid heater having hollow heating elements, means for passing one fluid through the elements and another fluid in contact with the other surface of the elements a multiplicity of times, and means for varying the number of passes for the latter fluid.

50 2. In combination, a duct adapted to supply air to a furnace, a preheater arranged in parallel with said duct, and means to deflect through said preheater either a part or the whole of the air passing through said duct.

55 3. In combination, a duct adapted to supply air to a furnace, a preheater arranged in parallel with said duct and having a plurality of passes through which the air may travel, means for deflecting air from said duct through said preheater, and means for varying the number of passes without substantially changing the amount of heating surface to which the air is exposed while passing through the preheater.

65 4. In combination, an air heater having a

plurality of heating elements, means to pass hot gases through said elements, means forming parallel spaces on opposite sides of said elements, a plurality of baffles extending across said elements to form passes communicating with said spaces, and a damper 70 in each of said spaces and each adapted when in one position to cooperate with one of said baffles to form an extension thereof and when in another position to permit air to flow past the end of the baffle. 75

5. In combination, an air heater having a plurality of heating elements, means to pass hot gases through said elements, means forming parallel spaces on opposite sides of said elements, a plurality of baffles extending across said elements to form passes communicating with said spaces, a plate in one of said spaces and extending lengthwise of said elements, and a damper pivoted on the side of said plate next the elements and adapted when in one position to cooperate with one of said baffles to form an extension thereof and when in another position to permit air to flow past the end of the baffle.

6. In combination, an air heater having a plurality of heating elements, means to pass hot gases through said elements, means forming parallel spaces on opposite sides of said elements, a plurality of baffles extending across said elements to form passes communicating with said spaces, a plate in one of said spaces and extending lengthwise of said elements, a damper pivoted on the side of said plate next the elements and adapted when in one position to cooperate with one of said baffles to form an extension thereof and when in another position to permit air to flow past the end of the baffle, and a damper on the other side of the plate and adapted to control passage of air through the space on that side of the plate. 95 100 105

7. An air heater comprising heating elements, means for passing a heating medium through said elements, means forming a plurality of air passes across said elements, said passes embracing substantially the entire heating surface of said elements, means for causing the air to flow in opposite directions in adjacent passes, and means for changing the direction of air flow in one of said adjacent passes to cause a parallel flow through both. 1115

8. An air heater comprising heating elements, means for passing a heating medium through said elements, means for causing air to flow over substantially the entire heating surface of said elements, and means for varying the number of passes taken by the air in its flow over said surface. 120

9. An air heater comprising heating elements, means for passing a heating medium through said elements, means forming a plurality of air passes across said elements, said passes embracing substantially the entire 130

heating surface of said elements, means for causing the air to flow in opposite directions in adjacent passes, and means for combining adjacent passes to form a larger pass.

- 5 10. An air heater comprising heating elements, means for passing a heating medium through said elements, means for causing air to flow over substantially the entire heating surface of said elements, means for varying the number of passes taken by the air in its flow over said surface, and means for bypassing the air around all of said elements.
